CLOTH SHIFTING LEVER FOR CLOTH LAYING MACHINES

Henry F. Meyer, St. Louis, Mo.

Application September 7, 1940, Serial No. 355,772

2 Claims. (Cl. 270—31)

This invention relates to improvements in a cloth shifting lever for cloth laying machines, it is used to guide the cloth as it is being spread and piled up on the cloth supporting table so that the edge of each layer of the pile will register evenly one upon the other, thus, when the pile of cloth is completed, the edge of the pile will be true and even all the way up.

The essential feature of the invention is, to provide a lever positioned in proper position in the cloth laying machine, over which the cloth passes while being spread and piled on the table, and as the machine is being directed from one end of the table to the other, the layer of cloth being spread and piled on top of the other layers already layed and piled is controlled by the manipulation of the lever so that its edge will register perfectly and evenly with the edges of the layers so piled below.

This lever is manipulated by the operator during the movement of the machine upon the table, and its handle is conveniently located so that access thereto may be had at all times during the travel of the machine from one end of the table back to the other end, and so on back and forth until the height of the pile is desired.

It is very essential, that the layers of cloth constituting the pile, have their edges register evenly, that is, one directly on top of the other, this is necessary on account of the patterning the pile for cutting. Should the edges partly overlap, there would be a certain amount of waste material caused by such overlap, which is considered of vital importance in the manufacturing of garments, as waste is an important item in the manufacturing art on account of the high cost of the materials used in the manufacturing of certain garments.

This lever as designed is an improved attachment to the cloth laying machine on which a patent was granted to Charles C. Schneider, June 11, 1940, Number 2,203,970, which Letters Patent is now under control of the National Cloth-Spreader Machine Company, of which applicant is a member.

Another object of the invention is the general arrangement, construction and combination of elements as will be hereinafter fully described and set forth in the claims.

Referring to the drawings:

Figure 1 is a side elevation of a cloth laying and spreading machine showing my improved shifting lever carried thereby.

Figure 2 is an enlarged detail view of a portion

of the machine carriage, showing the location and position of my shifting lever.

Figure 3 is a cross sectional view of the machine frame as taken on the line 3—3 of Figure 2, and viewing the same in the direction of the arrow.

Figure 4 is a detail cross sectional view, taken on the line 4—4 of Figure 2 showing the construction of the shifting lever handle, and viewing the same in the direction as indicated by the arrow.

Figure 5 is a perspective view of a portion of the cloth spreading machine frame or carriage, showing the shifting lever in relative position with the cloth to be layed.

Figure 6 is a detail top plan view of the shifting lever, showing its shifting positions.

In the general construction of my improved invention, I provide a lever mechanism positioned in the cloth laying and spreading machine carriage, which mechanism consists of a suitable shaft 7 on which is mounted a suitable roller 8, each end provided with a flange 9 and over this roller and between the flanges the cloth is adapted to pass during the laying process.

The shaft 7 is pivoted or swiveled at its one end in a suitable socket 10 formed and located on one side of the carriage and so arranged that the lever shaft may be shifted in positions as that shown by dotted lines, see Figure 6.

On the opposite projecting end 11 of the shaft 7 is positioned a latch grip handle 12 provided with suitable lips 13 through which a pivot is passed for retaining the grip handle in operative position, and between the handle 12 and the shaft is positioned a spring 14 which normally keeps the two suitably spread. On the handle is formed a latch dog 15 which is designed to engage between the teeth or cogs 16 formed on a plate or integral with a part of the carriage frame.

When it is desired to manipulate or shift the lever, the rod and handle is gripped by the hand and squeezed together compressing the spring consequently disengaging the latch dog 15 from the teeth 16 of the rack, by so doing the operator can move the lever in any suitable direction, either backward or forward as that shown by dotted lines in Figure 6. By this action it places a certain tension on the cloth which will direct the edge of the cloth either inwardly or outwardly while it is being layed upon the table. Consequently the operator through the manipulation of the lever can keep the edges of the

layers even and without any overlappage or underlappage.

In Figure 5 I show in the perspective view the position of the lever relative with the cloth as it passes through the laying machine, the cloth shown in the machine is designated by the numeral 17 passing from its mounted roll 18 over guide rollers 19 and 20, then over the shifting lever roller 8, and over a roller 21, then down through the spreading means 22 and positioning it upon the table and piled as indicated by the numeral 23.

The shaft of the roller 21 is provided with a bevel pinion 24 which meshes with a bevel gear 25 attached to a shaft 26, one on each side of the roller shaft, this shaft is in the nature of a screw contacting with a guide block 27 for raising and lowering the spreading mechanism, and regulating it as the pile becomes higher and being built up to the desired height required.

This feature, however, is not a part of this invention, it was only referred to as a matter of information.

The essential feature of the invention is the shifting lever mechanism, the manner of its position with the cloth, and its mode of operation for the directing the cloth so that its edge will properly register with the layer of cloth already layed on the table.

Some and other changes may be made in the construction and arrangement of the invention above set forth without departing from the real spirit and purpose thereof; and it is my intention to cover by the following claims any modified form of structure or use of equivalents which may be reasonably included within their scope.

I claim:

1. A cloth shifting lever for cloth laying machines comprising a lever mechanism operating in combination with a cloth laying machine, said lever comprising a roller, a shaft supporting the same, said shaft pivotally mounted at one end to the machine frame, a handle on the free end for manipulating the lever, and a latching means for locking the shaft when in horizontal adjusted position.

2. A cloth shifting lever of the character described comprising a lever pivotally connected to a machine frame, said lever consisting of a shaft, a roller mounted thereon, a handle positioned on the free end of the shaft, a latch means carried by the handle which is to engage with teeth formed on the machine frame, said roller contacting with the cloth to be layed as it passes through the machine, and by the manipulation of said roller the position of the cloth on the pile is regulated so that its edges register evenly.

HENRY F. MEYER.
